(57) **CLAIM**

We claim the ornamental design for a vascular closure apparatus, as shown and described.

DESCRIPTION

FIG. 1 is a front side elevational view of a vascular closure apparatus;

FIG. 2 is a left side elevational view of the vascular closure apparatus of FIG. 1;

FIG. 3 is a rear side elevational view of the vascular closure apparatus of FIG. 1;

FIG. 4 is a right side elevational view of the vascular closure apparatus of FIG. 1;

FIG. 5 is a perspective view of the vascular closure apparatus of FIG. 1;

FIG. 6 is a top plan view of the vascular closure apparatus of FIG. 1; and,

FIG. 7 is a bottom plan view of the vascular closure apparatus of FIG. 1.

The broken lines shown in the drawings are for the purpose of illustrating environment and form no part of the claimed design.
